UNITED STATES PATENT OFFICE.

JAMES MORTON, OF DENTONHILL, CARLISLE, ENGLAND.

MANUFACTURE OF TAPESTRY OR PRINTED CARPETS, RUGS, TABLE-COVERS, AND THE LIKE.

1,391,785.

Specification of Letters Patent. Patented Sept. 27, 1921.

Application filed April 4, 1919. Serial No. 287,638.

To all whom it may concern:

Be it known that I, JAMES MORTON, of Dentonhill, Carlisle, England, a subject of the King of Great Britain, have invented 5 certain new and useful Improvements in the Manufacture of Tapestry or Printed Carpets, Rugs, Table-Covers, and the like, of which the following is a specification.

This invention relates to the manufacture 10 of tapestry or printed fabrics, such as carpets, rugs, table covers, and the like.

In the well known art of printing varicolored yarns on drums, the printed yarns to be subsequently used as pile warps in the 15 manufacture of looped pile and velvet pile "tapestry" carpets, rugs, table covers, and the like, (hereinafter referred to generally as carpets or the like) it has hitherto been usual to print, in one continuous 20 thread, the warp necessary for the entire length of the article, that is to say, from the beginning of the bottom cross border to the end of the top cross border. It has thus been necessary to have different sized drums 25 for every desired length of carpet or the like, and, in the case of large carpets or the like, very large and very expensive printing drums have to be employed. Owing 30 to the great cost of these large drums the manufacture of large tapestry carpets has been much curtailed, indeed it has been considered impracticable to make carpets longer than, say, 15 feet in length.

The method at present in use involves 35 keeping large stocks of warp of every individual size and coloring wanted for the different designs with the result that the manufacturer has either to limit his "ranges" to a few sizes and colorings or risk keeping 40 very heavy stocks.

My invention has for its object to obviate the necessity for employing a large number of printing drums of varying sizes and especially to obviate the employment of the 45 large expensive and unwieldy drums, while, at the same time, with much smaller stocks, giving every facility for the production of printed carpets or the like, of indefinite length and of a variety of sizes.

Under my invention I use a printing drum 50 of a size sufficient to print the required length of printed warp yarn for both the bottom and top cross borders and I "set" 105

this printed yarn on one beam, hereinafter referred to as the "border beam", and then, 55 it may be on the same drum, or, on any drum preferably of the same size, I print "filling" warp yarn for the body or center of the article and set it on another beam herein-after referred to as the "filling beam". In 60 the process of weaving, on the tapestry loom, while the cross borders are being woven, the heddles controlling the filling warp are put out of operation and the yarn held so as not to become part of the cloth or 65 to be "taken up" in any way; similarly, when the "filling" is being woven the yarn from the "filling" beam is put into action and is allowed to work one, two or more repeats, according to the size of the carpet or 70 the like desired while the yarn from the "border" beam is put out of action.

The warp yarns to be held inactive may be raised by passing a rod under them and then holding them by a clamp whereupon 75 the warp ends are cut out. The clamp is fastened to the top part of the lathe. In this way the inactive threads are held above the operating warps. The warp ends are reinserted into the fabric and are woven in 80 by successive weft threads before cutting out the original set of warps held out of use. In one arrangement the rod is detachably attached to the upper part of the lathe with the warp ends temporarily held out of use 85 until they are to be again inserted into the fabric. After being reinserted into the fabric by removing the rod and floating a succession of weft threads into place the unused portions of the warp ends can be cut 90 away.

In practice, as will be understood, it is not, of course, necessary to print the warp for the "body" on, actually, the same drum as that used for the cross border yarn or on 95 a drum the same size. The drum used may be the same, and, in practice, would preferably be the same size, so as to maintain a uniform standardized size of drum throughout the plant, but it may be smaller or larger 100 as required by the repeat of the pattern. The essential point, however, is that since I print the body design separately from the cross borders I am enabled to use a drum small enough to print only one repeat of the 105 body design instead of, as usual, using a

drum representing the full length of the carpet or the like and embracing not only the cross borders but even several repeats of filling as well.

- 5 If the article being manufactured is to have side borders as well as cross borders then a separate printing is made for the side borders. The yarn for the side borders may be put on the filling beam or it may be put 70
 10 on a separate beam, according to requirements of design, but if put on a separate beam this beam would operate always in the weaving process in conjunction with the filling beam and be put into and out of action 75
 15 therewith.

In order that the invention may be clearly understood I have appended drawings showing, simply by way of example, the mode of manufacturing a rug in its simplest form 80
 20 with filling and bottom and top cross borders and also a carpet with complete border all around.

In the case of the rug Figure 1, which may be, for example, 6'-8" long with the cross 85
 25 borders each 8" wide, then the printing drum would be, simply, of a size sufficient to print pile warps for filling and for borders of a length to give, when woven, 1'-4". The printed yarn for the cross borders *a*, *b*,
 30 is set on one beam (beam No. 1) and the yarn for the filling on another beam (beam No. 2) and the border yarn is first thrown into action for weaving the bottom cross border *a* and is then suspended while the
 35 filling yarn is put in action and continues in four repeats *c*, *d*, *e*, *f*, each 1'-4", so as to give a total length of filling of 5'-4" when the filling is suspended and the border yarn again thrown into action to complete
 40 the top cross border *b*. The borders being each 8" together make up 1'-4", the same as the filling repeats so that it is obvious one printing drum can be used for both and its size need only be sufficient to give
 45 the necessary length of yarn for each repeat. The filling need not, of course, have a repeat 1'-4", in which case, if the repeat was other than 1'-4" or a multiple of 1'-4", it would be printed on a drum of a different size.

If the rug is to have side borders as well as cross borders, then special printing would be made to suit the side borders just as in the case of the filling yarn. The yarn for 55
 55 the side borders and filling would be set on the same beam or on separate beams according to the requirements of the design. Preferably we would use separate beams and set the filling on a beam *2^a*, and the side
 60 border yarn on a beam *2^b*, but both these beams would operate simultaneously in the process of weaving, and be put in and out of action simultaneously to suit the operation of the cross borders as described.

65 The above is the procedure presuming a

single article is being woven, but, of course, the rugs would be woven continuously (see A. B. C. Fig. 1) and, therefore, the top cross border of the one rug A and the bottom cross border of the next rug B would be 70 on the same "border" beam and the double border would read forward from *x* to *y* and then backward from *y* to *x¹*, the total width of the double border *a*, *a¹*, as well as *b*, *b¹*, being equal to that of each repeat of the 75 filling.

In the case of a carpet as at Fig. 2, of say, a length of 12 feet and a width of 9 feet with each cross border of 18" and the double cross border 3 feet, then the filling 80 and side borders would be in three repeats *g*, *h*, *i*, of 3 feet each so that the printing drum need only be of sufficient size to give 3 feet of pile warp when woven.

It will be obvious to those acquainted with 85 the art that the procedure may be varied such as by using a beam for the cross border yarn and a separate beam for the corner yarn both beams being thrown into and out of action simultaneously; also, that 90 printed carpets can be made of different lengths, while using the same size of printing drum, by varying the repeats of the filling these repeats being preferably a multiple of the width of the double cross border. 95

Owing to the fact that the body yarn may be on a filling beam which is entirely independent of the border beams, it is possible to weave any variety of printed body or body made with colored dyed yarns with 100 the same borders, and by changing the filling beam only. Thus if the beams with border yarns contained sufficient length to weave 40 carpets, instead of those 40 carpets being the same as to color and size as at 105 present, it would be possible to weave, say 10 with printed pattern body, red ground prevailing; 10 with printed pattern body, blue ground prevailing; 10 printed pattern body, cream ground prevailing; and a further 10 woven with body warps made from, says, red dyed yarn. These would all be woven with the same border and could be woven in any variety of lengths in the various carpets.

115 This capacity of being able to have any variety of body, either printed or made from plain dyed yarns, independent of borders, is rendered possible by printing the yarn for the borders separately from 120 that for the body, and operating it in the weaving process independently of the body. It is of course possible, vice versa to have a variety of borders with the same body, also for the border to be made of dyed yarns 125 and the body printed, though the method above described of varying the body, and maintaining the same borders during a "weaving," will be found, in practice, to be the most useful. It will therefore, be seen 130

that the process described gives a much enhanced value to this type of article, thus affording an endless variety in general design at small cost and without involving 5 heavy stocks.

It will be evident that the above description refers to carpets or the like with a defined border and a repeating or plain filling as distinct from what are known as 10 "medallion" designs, but the method also applies to designs of the "medallion" type which reverse at the center of the carpet or other article. In such types the improved method enables drums to be used of only 15 half the circumference of those presently in use and involves only half the stocks for the same size of drum. The warp thread is printed to the center of the medallion only and is, afterward, set on two separate beams, 20 one beam having been set with the pattern reading "Forward," the other with the pattern reading "Backward." These two beams are then used in the loom as before described the one being out of operation while the 25 other is weaving, thereby forming a complete medallion design.

The following advantages arise from the method of manufacture as hereinbefore described.

30 There is considerable economy in the initial outlay for plant and, owing to the fact that a uniform standardized size of drum can be used for various lengths and designs of carpets, there is great economy and 35 facility in the running of the plant. Any size of carpet or the like can be produced with a small sized drum, and a bordered carpet, or the like, can be produced of indefinite length, which is impossible at present. 40 A much greater variety in design and coloring can be produced from the same amount of printing, and there is no necessity, consequently, for keeping large stocks of any given size or coloring.

45 There may be produced, at will, from the same printed warps, carpets of different lengths, one after the other, instead of having to make them all of the same length as at present. There is also given the facility 50 of weaving a variety of printed designs and colorings with the same borders and vice versa, also a dyed yarn can be used for the filling, while the borders (cross and side) may be made of printed yarns, or vice 55 versa, thus giving an enhanced value to this class of goods.

Having now fully described my invention what I claim and desire to secure by Letters Patent is—

60 1. A method of manufacturing tapestry or printed carpets, and the like, in which the yarn for forming the cross borders is first printed on a printing drum independently 65 of the warp yarn for the body of the fabric and is then, in order to be woven, beamed

on separate beams and, during the weaving process, the body yarn is put out of action and held so as not to form part of the cloth when the cross border yarn is in action, and vice versa, substantially as described.

70

2. A method of manufacturing tapestry or printed carpets and the like in which a printing drum of a size for printing the required length of warp yarn for both the bottom and top cross borders is used and the yarn 75 printed thereon and, after being printed, is set on a weaving beam and, then, on the same drum, the warp yarn for the body of the carpet is printed and subsequently set on a separate weaving beam, the yarns from 80 the beams being thereafter woven on a tapestry loom and, while the cross border yarn is being woven in the loom the heddles controlling the body warp yarns are put out of operation and the yarn held so as not to 85 become part of the cloth, while, when the body of the carpet is being woven the body yarn is put into action and is allowed to work one or more repeats the heddles controlling the border yarn being then put out 90 of action and the cross border yarn held so as not to become part of the cloth, substantially as described.

3. A method of manufacturing tapestry or printed carpets and the like in which a 95 printing drum of a size for printing the required length of warp yarn for both the bottom and top cross borders is used and the yarn printed thereon and after being printed is set on a weaving beam and, then, 100 on a drum of the same size, the warp yarn for the body of the carpet is printed and subsequently set on a separate weaving beam, the yarns from the beams being thereafter woven on a tapestry loom and, while the cross border yarn is being woven in the loom, the heddles controlling the body warp 105 yarns are put out of operation and the yarn held so as not to become part of the cloth, while, when the body of the carpet is being 110 woven the body yarn is put into action and is allowed to work one or more repeats the heddle controlling the border yarn being then put out of action and the cross border 115 yarn held so as not to become part of the cloth, substantially as described.

4. A method of manufacturing tapestry or printed carpets and the like in which a printing drum of a size for printing the required length of warp yarn for both the bottom and top cross borders and corners is used and the yarn printed thereon and after being printed is set on a weaving beam and, then, on the same drum or a drum the same size, the warp yarn for the body and side 120 borders of the carpet is printed and subsequently set on a separate weaving beam, the yarns from the beams being thereafter woven on a tapestry loom and, while the cross border and corner yarn is being woven 125 130

in the loom the heddles controlling the body and side border warp yarns are put out of operation and the yarn held so as not to become part of the cloth, while, when the body 5 of the carpet is being woven the body and side border yarn is put into action and is allowed to work one or more repeats the heddles controlling the border yarn being then put out of action and the cross border 10 yarn held so as not to become part of the cloth, substantially as described.

5. The method of manufacturing tapestry or printed carpets and the like in which the warp yarn for the body design of the carpet 15 is printed separately from the cross border yarn, the printing being effected on a drum small enough to print only one repeat of the body design, the printed cross border yarn and the printed body yarn being set on separate beams and woven in the tapestry loom the cross border yarn being put out of 20 action when the body and side border yarn is in action, and vice versa.

of action when the yarn from the other beam is in action and vice versa.

6. The method of manufacturing tapestry or printed carpets and the like in which the 25 warp yarn for the body design of the carpet is printed separately from the cross border yarn, the printing being effected on a drum small enough to print only one repeat of the body and side border design, the 30 printed cross border yarn and the printed body and side border yarn being set on separate beams and woven in the tapestry loom the cross border yarn being put out of 35 action when the body and side border yarn is in action, and vice versa.

In testimony whereof I affix my signature in presence of two witnesses.

JAMES MORTON.
